BUTTON

Louis Richmond and David Eckert, New York,
N. Y.Original application May 7, 1938, Serial No.
206,568. Divided and this application Janu-
ary 24, 1939, Serial No. 252,538

1 Claim. (Cl. 24—90)

This invention is divided out from our co-pending application, filed May 7, 1938, bearing Serial #206,568, now Patent No. 2,150,563, granted March 14, 1939, and relates to buttons generally and more particularly to buttons adapted for use in connection with fur coats or coats made of heavy fabrics, and has for one of its objects the provision of a shankless button, which, instead of being sewn to the garment is tied thereto by means of a tape or the like carried by the button.

Another object of the invention is the provision of a button of the nature referred to, in which the securing tape is not visible from the front or outside of the button.

15 A further object of the invention is the provision of such a button comprising a solid disc having a flat bottom surface at an angle to which are drilled a pair of spaced apart holes, the said holes meeting at the center of the disc, intermediate its top and bottom surface, to provide means for passing a securing tape therethrough and to further provide a pair of elliptical entrance openings into either of which the tape may be easily inserted for threading or drawing same through the button.

20 Another object is to produce a device of the character described in which the maximum simplicity of construction and operation is secured.

Other objects and advantages will appear as 25 the nature of the improvements is better understood, the invention consisting substantially in the novel arrangement and co-relation of parts herein fully described and illustrated in the accompanying drawing, wherein similar reference characters are used to describe corresponding parts throughout the several views, and then finally pointed out and specifically defined and indicated in the appended claim.

The disclosure made the basis of exemplifying 30 the present inventive concept suggests a practical embodiment thereof, but the invention is not to be restricted to the exact details of this disclosure, and the latter, therefore, is to be understood from an illustrative, rather than a restrictive stand- 35 point.

In the accompanying drawing—

Figure 1 is a sectional view of our improved button showing same secured to the coat fabric; and

50 Fig. 2 is a bottom plan view of the button.

Some buttons now commonly used in connection with heavy fabrics and fur coats are of the type which include a shank by which means they are secured to the coat. The aforementioned shanks comprise a wire loop imbedded in the but-

ton disc which often break off, such breakage causing, besides the loss of the button, extra labor in securing a new button in place.

Other buttons commonly used are provided with bulging perforated shanks stamped out of sheet metal which cause the buttons to stand away from the coat material and give the garment a rather clumsy appearance. Such buttons are expensive to manufacture and often come apart at the juncture of the shank and upper body portion thereof. It is to obviate these undesirable features that we have perfected the button of our present invention.

Referring now to the drawing in detail, 5 indicates a solid disc button which may be made of any desirable material and provided with a flat even bottom surface 6 at an angle to which are drilled, or otherwise formed, a pair of spaced apart holes or openings 7 which meet at a central point 8 intermediate the top and bottom surfaces 20 of the disc. Due to the angularity of the holes with the bottom surface of the button, a pair of spaced apart elliptical entrance or mouth openings 9 are formed to provide easy and ready access for the securing tape 10 when threaded 25 through the openings 7.

The button may be kept in stock with the tape 10 knotted or tied about the central portion 11 until needed for use, at which time the free ends of the tape are passed through the coat material 12 and tied as at 13 for securing the button to the coat. The original knot about the central portion 11 (not shown), may or may not be opened when the button is secured to the coat material. In Fig. 1 of the drawing, the button 35 is shown against the coat material with the original knot having been opened and the tape knotted at 13 after it has been passed through the coat material 12.

From the foregoing, it will be seen that we 40 have provided a one-piece inexpensive shankless button which is made of a single solid disc, the said disc having means through which a securing tape may be readily passed, the said tape not being visible from the exterior of the button.

45 It will also be seen that due to the construction of the button, there are no parts to become loose or broken, and the button may be drawn as close as desired to the material to which it is secured due to its even flat bottom surface.

Having described our invention, what we claim 50 as new and desire to secure by Letters Patent is:

A one-piece solid button comprising a solid body having a substantially flat bottom face, said body being formed with a passage for receiving 55

a securing strand and consisting of straight end sections leading forwardly from the bottom face thereof in spaced relation to each other, said end portions having their front ends intersecting in spaced relation to the front face of the body and communicating with each other to form a continuous angular passage, the outer ends of the

said end sections opening through the bottom face of the body to form elliptical mouths to facilitate passage of a securing strand through the passage.

LOUIS RICHMOND. 5
DAVID ECKERT.
